(57) **CLAIM**

The ornamental design for an electrical controller, as shown and described.

DESCRIPTION

FIG. 1 is a top view of an electrical controller according to my design;

FIG. 2 is a bottom view thereof;

FIG. 3 is a rear view thereof;

FIG. 4 is a front view thereof;

FIG. 5 is a left view thereof;

FIG. 6 is a right view thereof; and,

FIG. 7 is a right, rear, top perspective view thereof.
